United States Patent Office

Des. 211,808
Patented July 30, 1968

211,808

TOY HOISTING TRUCK

Robert Genin, Scarsdale, N.Y., assignor to Child Guidance Toys Inc., Bronx, N.Y., a corporation of New York

Filed July 18, 1967, Ser. No. 7,853

Term of patent 14 years

(Cl. D34—15)

FIG. 1 is a perspective view of my design for a toy hoisting truck whose body is transparent, to reveal the inner working gears;

FIG. 2 is a plan view of the truck;

FIG. 3 is a front end view; and

FIG. 4 is a rear end view.

I claim:

The ornamental design for a toy hoisting truck, substantially as shown and described.
